UNITED STATES PATENT OFFICE

2,503,328

JACK

Maurice Frimet, Staten Island, N. Y.

Application March 17, 1947, Serial No. 735,060

1 Claim. (Cl. 254—88)

1

This invention appertains to novel and useful improvements in lifting devices particularly adapted for use in raising selected portions of vehicles.

An object of this invention is to provide an improved lifting device or jack having means for actuating the same accessibly and easily from the side of a conventional vehicle.

Another object of the invention is to provide extension means for receiving a selected wheel of a vehicle thereon.

A further object of this invention is to provide means both selectively and detachably secured to the lifting means for engaging selected portions of a vehicle.

A still further object of this invention is to provide a novel and improved device of the nature described characterized by ease of operation, facility in actuation, obviating the necessity of placing and actuating a lifting device from the front or rear portion of a vehicle.

Ancillary objects and features of novelty shall become apparent to those skilled in the art, in following the description of the preferred embodiment of the present invention, illustrated in the accompanying drawings, wherein:

Figure 1 is an elevational side view of the preferred embodiment of the present invention, parts being shown in section to illustrate details of construction and showing the preferred form of operating the invention when used in conjunction with an automotive vehicle;

Figure 2 is an elevational side view of the preferred form of the present invention;

Figure 3 is a sectional view of the invention disclosed in Figure 1 and taken substantially on the line 3—3 thereof and in the direction of the arrows;

Figure 4 is a transverse sectional view, taken substantially on the line 4—4 of Figure 1 and in the direction of the arrows;

Figure 5 is a sectional view of the invention disclosed in Figure 4 and taken substantially on the line 5—5 thereof and in the direction of the arrows;

Figure 6 is a fragmentary elevational view, showing particularly one form of the detachable extension means forming part of the present invention;

Figure 7 is a longitudinal sectional view of the invention disclosed in Figure 5 and taken substantially on the line 7—7 thereof and in the direction of the arrows, and

Figure 8 is a transverse sectional view showing a detail of construction in Figure 1 and taken

2

substantially on the line 8—8 thereof and in the direction of the arrows.

Referring now in detail to the illustrated preferred embodiment of the present invention, like reference characters are used throughout to indicate elements of similarity.

This invention has been developed to provide an improved device for facilitating repair operations of vehicles, particularly such operations which entail the removal of a wheel, brake drum or other associated adjacent mechanism. In the newer model automotive vehicle, an appreciable amount of body portion protrudes over the front and rear axles thereof. Also, it is the tendency of automotive vehicle manufacturers to extend the vehicle as close as practicable to the road. It is known that this type of construction gives rise to difficulties in using certain conventional types of jacks and also, the utility of jacks for lifting the vehicle from contact with bumpers and the like have proved to be unsafe and generally unsatisfactory in operation. It is within the purview of the present invention to provide a device for lifting selected portions of automotive vehicles without resorting to contacting bumpers and without resorting to insertion of the jack from the front or rear portion of the vehicle.

A base member 10 is provided of some suitable material, preferably metallic, and has an extension 12 secured thereto. To assist in manufacture, the said base member and extension may be constructed of two or more elements if so desired. This however, is a mere matter of choice in construction to aid in commercial practicability.

A lifting means is provided in the said base 10, while a portion thereof extends through the extension 12. Any form of conventional lifting means may be utilized in conjunction with the present invention, either mechanical, hydraulic or compressed air actuated. For illustration purposes, a mechanical lifting means is provided.

A sleeve 14 is rotatably received in a suitable bore 16, provided in the said base 10. A slot 18 extends longitudinally of said bore 16 and a pin 20, secured to said sleeve 14, is reciprocatively journaled in the said slot 18. This construction prohibits rotational movement of the said sleeve 14, as is conventional in the art. A threaded screw 22 is received in the threaded bore of the said sleeve 14 for the purpose of imparting motion parallel to the longitudinal axis of the said sleeve. The usual, conventional gear 24 is pinned or otherwise secured to a terminal portion of the said screw 22. It will be noted

from an inspection of Figure 4 that the unthreaded shank 26 of the said screw 22 extends through the center of the said gear 24 and is journaled in a suitable aperture at the base of said base member. A shaft 28 is rotatably journaled in the base 10 and extension 12, extending therethrough. A suitable, conventional thrust bearing 30 is provided in the extension 12 and may be secured to the said shaft 28 in abutting relation to the interior of the extension. A worm 34 is received on the said shaft 28 and engages the gear 24. It is quite apparent from an inspection of Figure 4 that rotation of the said shaft 28 produces movement of the sleeve 14 parallel to the longitudinal axis thereof.

A conventional receptor 36 is secured to the said shaft 28 exteriorly of the extension 12. This receptor is provided for the purpose of receiving a conventional handle mechanism 38 removably therein.

It is noted at this point that the aforementioned sections of the base and extension may be joined by any suitable conventional means including welding, brazing, riveting or as disclosed by suitable conventional bolts 40 and associated nuts 42. As many of these bolts may be employed as dictated by sound engineering principles.

The said extension 12 is preferably provided with a ramp 46 at one end thereof to facilitate the entry of a vehicle wheel thereon. As is quite apparent from an inspection of Figure 1, the invention is simply placed in front of a wheel to be removed and the vehicle is moved forward thereon. Obviously, all of the actuating mechanism to be treated manually within a convenient location extending perpendicularly from the side of an automotive vehicle. A recess 48 may be provided at the upper portion of said extension 12, thereby forming guide means in holding the tire 50 of a conventional wheel therein.

Various types of vehicles are provided with different types of spring suspension, steering gear and the like. In order that the present invention may be utilized with substantially all types of commonly known vehicles, arms are selectively and detachably secured to the upper portion of the said sleeve 14. Any suitable securing means is utilized in attaching variously configured arms to the upper portion of said sleeve. A slotted extension 52 may be secured to the said sleeve 14 and intersecting apertures may be provided in the arm 54, said last mentioned apertures being complementary to the slotted extension 52. The arm or extension means 54 may be rested upon the sleeve 14 and a conventional pin extended through one of the said intersecting slots. The arm 54, disclosed in Figure 2, will engage suitable under carriage elements of most conventional vehicles; however, variation as to shape and size of the said arm 54 may be employed in certain instances.

Referring now to Figure 6, it is quite evident that a dovetail construction is illustrated, the male member 58 provided on the sleeve 14 while the female member 59 is provided in the arm 60. It is noted that this arm 60 is provided with two right angular bends, a slot 62 being provided

5
10

in the lower of said bends. This construction permits the engagement of the slot 62 with a brake drum or similar braking element. This type of construction is employed when it is impractical to use one of the arms of the class described and disclosed at 54. Of course, if found desirable, the dovetail construction disclosed in Figure 6, might be employed in the construction of Figures 1 to 5 in lieu of the securing means disclosed therein.

60

In operation, all that is necessary to position the jack in the desired operative position is to place the same in the front of the wheel to be removed and drive or otherwise move the vehicle on the extension and in the recess 48. Then, actuation of the handle means 38 moves the selected arm 54 or 60 against a suitable element of the under carriage of a vehicle. The said under carriage is then lifted until the wheel and tire is out of contact with the extension 12. The wheel or wheel component may then be easily removed for repair or other purposes. It is well to note at this point that the operator of the invention need never crawl under his vehicle for the removal of a wheel having a deflated tire thereon.

It is apparent that a device capable of performing all of the specifically mentioned objects has been described herein. However, it is apparent to those skilled in the art, that various changes including omissions, additions and rearrangement of elements may be made herein without departing from the spirit of the invention. Accordingly, limitation is sought only in accordance with the scope of the following claim.

Having thus described the present invention what is claimed as novel and improved is as follows:

In a lifting device, a base having an extension integral therewith, a jack in said extension, means extending through said base and terminating in said extension for actuating said jack, an inclined ramp formed in said base for reception of a vehicle wheel, said extension projecting a substantial distance from the ramp to prevent tipping of the base, means detachably secured to the jack for clampingly engaging a brake drum, said last mentioned means comprising an arm having a dovetail slot for detachable association with the jack, right angular bends in said arm, one of said bends being formed with a slot in the upper surface thereof for accommodation of a brake drum flange.

MAURICE FRIMET.
